UNITED STATES PATENT OFFICE.

BERNARD D. COLEN, OF NEW YORK, N. Y.

RADIO JUNCTION BOX.

Application filed July 1, 1924. Serial No. 728,529.

This invention relates to radio junction boxes which may be permanently connected to the antenna, ground and batteries, and detachably connected to a radio set so that 5 the set may be removed or re-connected by a simple single operation.

An object of the invention is to provide an improved junction box of this type, with which there will be no danger of a misconception 10 of the set to the batteries or other circuit wires, which may also serve as a housing for a lightning arrester and which is relatively simple, compact and relatively inexpensive. Various other objects and advantages will appear from the following description 15 of an embodiment of the invention, and the various novel features will be particularly pointed out hereinafter in the appended claims.

20 In the accompanying drawing, Figure 1 is a perspective of a junction box constructed in accordance with the invention.

Fig. 2 is a plan of the base of the same with the cap removed.

25 Fig. 3 is a plan of the under face of the cap.

Fig. 4 is a plan of the under face of the base, and

30 Fig. 5 is a transverse sectional elevation of the box, the section being taken transversely along the line 5—5 of Fig. 2.

In the illustrated embodiment of the invention, a base member 1 may be molded 35 from suitable insulating products or materials such as hard rubber or phenolic condensation products. The base is provided with superposed cavities 2 and 3 separated by a partition wall 4 of dielectric composition and opening respectively into the upper and

40 lower faces. The upper cavity 2 may be closed by a plate 5 such as a glass or mica sheet that may be held in position by a split ring 6 overlying the periphery of the closure plate 5 and springing into an undercut 45 groove in the periphery of the cavity, the plate fitting against a shoulder in the cavity. The lower cavity 3 may be closed by a plate 7 which is countersunk into the bottom face 50 of the base member and secured to the base member removably in any suitable manner such as by screws 8.

A plurality of contact sockets 9 are molded or otherwise inserted into the base member 1 so as to extend from the lower cavity 3 to the 55 upper face of the base member without passing through the upper cavity 2. The upper

ends of the socket members terminate some distance below the upper face of the base member and the base member is provided with passages extending from the upper face 60 thereof to the socket members, the passages having diameters corresponding in size to the bores of the socket members and aligned therewith so as to form substantial continuations of the bores of the socket members. 65 The socket members at their lower ends are provided with suitable means such as screws 10 serving as terminals for the attachment of circuit wires 11 running from the antenna, ground and batteries, there being a separate 70 circuit member for each circuit wire.

The battery wires may enter the junction box in the form of a cable 12 passing through an aperture 13 in a lateral wall of the base member and the antenna and ground wires 75 14 and 15 respectively may enter the cavity 3 through special passages 16 and 17 in the lateral wall of the casing. The antenna and ground wires are connected preferably to two diametrically opposite contact sockets 80 and these particular contact sockets to which they are connected have fitted over them plates 18 which extend into the upper cavity 2. Suitable electrodes 19 are secured upon these extension plates 18 in any suitable 85 manner, such as by screws 20, the electrodes extending toward one another and having their tips spaced slightly apart so as to form a spark gap or static gap which is commonly called a lightning arrester. Thus if the 90 charge on the antenna becomes sufficient to jump the gap between the electrodes, it will pass to ground and not enter and injure the set.

A cap member 21 of insulating material 95 is adapted to fit flat against the upper face of the base member and has a removable section 22 which is secured to the main section in any suitable manner, such as by screws 23, which pass upwardly into the section 22 from 100 the lower face of the body and cap member. The base part of the cap member and the removable section 22 have co-operating cavities upon their abutting faces so as to form a chamber or cavity 24. A plurality of contact pins 25 are passed through or molded into the base part of the cap member so as to extend from the chamber 24 through the cap member and depend therefrom. The contact pins 25 are arranged on the cap member in 110 the same order and spacing as the contact sockets, so that all of the pins will enter cor-

responding socket members in the base member whenever the cap member is brought into a particular position against the base member. The depending ends of the contact pins 5 are preferably provided with slits 26 extending from the free end approximately to the under surface of the cap member so that when inserted into the contact members the divided ends will be sprung together by the 10 socket members in order that a good electric contact may be established between them.

The contact pins 25 may be provided upon their upper ends within the cavity or chamber 24 with suitable means for the attachment 15 of circuit wires, such means being as illustrated, terminal screws 27, which are threaded into the upper ends of the pins. The circuit wires from the set may be included in a cable which enters the chamber 20 or cavity 24 through an aperture 29 in the cap member, the circuit wires 30 of the cable 28 being separated within the cavity or chamber 24 and connected individually to the separate contact pins.

25 In the use of the device, the antenna, ground and battery wires from the set are included within the cable 28 and properly connected to the contact pins in the cap member. The antenna lead 14 and the 30 ground lead 15 are connected to the contact sockets of the base member, which are electrically connected to the electrodes, so that the accumulation of an injurious or excessive potential upon the antenna lead will be 35 prevented, since the potential will jump the gap between the electrodes and pass directly to the ground through the ground lead. The battery wires coming directly from the batteries are included in the cable 12 and 40 after entering the base member the battery wires are separated and connected properly to the various contact sockets so that when the cap member is applied to the base member, the circuit wires coming from the set 45 will be properly connected to corresponding circuit wires running to the batteries and to the antenna and ground.

To disconnect the set so that it can be removed, it is necessary merely to pull upwardly upon the cap member, which will 50 remove all the pins from the sockets and break the electrical connections to the set. It will be noted that during this disconnection the lightning arrester or protector will 55 still be effective in the base member. To re-connect the set it is necessary merely to reapply the cap member to the base member with the contact pins entering the sockets to re-establish electrical connections. In order 60 to avoid the possibility of getting the wrong pins in the sockets, special aligning pins or dowels may be provided, but preferably the contact pins and sockets are irregularly spaced so that they will all only be in alignment in one relative position. Thus, under

such an arrangement, there can be no possibility of putting the pins in the wrong sockets. Since the contact sockets terminate some distance below the upper surface of the base member, there can be no danger of an 70 improper connection between the pins while the correct relative relation for establishing the proper connection is being made. That is, it will be necessary to present the cap with the pins in the proper relation to the 75 base member before any pins can be inserted far enough into the sockets to establish a connection with the contact sockets. This effectively prevents any danger of accidental 80 misconnections by inexperienced operators. 85

It will be obvious that various changes in the details and arrangement of parts which have been herein described and illustrated for the purpose of explaining the nature of the invention and one embodiment 85 thereof, may be made by those skilled in the art within the principle and scope of the invention as expressed in the appended claims.

I claim:

1. A radio junction box comprising base 90 and cap members of insulating material, the base member having two superposed cavities divided by an insulating wall, contact sockets disposed in passages of the base member leading from one of said cavities to the upper face, the ends of the sockets in said one cavity having terminals for the attachment of circuit wires, contact pins to which circuit wires may be connected carried by and projecting from a face of the cap member 95 in an arrangement corresponding to that of the sockets whereby when brought together in a determined relation the pins may enter and contact with the sockets, spark gap electrodes in the other of said cavities and electrically connected to two of said sockets to 100 which the antenna and ground circuit wires are to be connected, whereby the electrodes will serve as a lightning protector. 105

2. A radio junction box comprising base 110 and cap members of insulating material, the base member having two separate superposed cavities, one in top and the other in the bottom faces, contact sockets in passages in the base member leading to the upper 115 face from the lower cavity and having in said lower cavity suitable terminals for the connection thereto of circuit wires, contact pins to which other circuit wires may be connected carried by the cap in an arrangement corresponding to the arrangement of 120 sockets whereby when the members are brought together in a determined relation the pins may all enter and contact with the sockets and conductors leading from those 125 sockets to which the antenna and ground wires are to be connected into the upper cavity and mounting electrodes of a spark gap.

3. A radio junction box comprising base 130

and cap members of insulating material, the base member having two separate superposed cavities, one in top and the other in the bottom faces, contact sockets in passages 5 in the base member leading to the upper face from the lower cavity and having in said lower cavity suitable terminals for the connection thereto of circuit wires, contact pins 10 to which other circuit wires may be connected carried by the cap in an arrangement corresponding to the arrangement of sockets whereby when the members are brought to-

gether in a determined relation the pins may all enter and contact with the sockets, conductors leading from those sockets to which 15 the antenna and ground wires are to be connected into the upper cavity and mounting electrodes of a spark gap, and a removable plate closing the upper cavity to prevent the entrance therein of the contact pins when 20 the pins are improperly presented.

In testimony whereof I have hereunto set my hand.

BERNARD D. COLEN.
